ABSTRACT OF THE DISCLOSURE

Hydrogen peroxide is used in the treatment of dirty dry cleaning baths based on aliphatic hydrocarbon or chlorinated solvents, to permit longer operation between distillations.

BACKGROUND OF THE INVENTION

In the dry cleaning of garments and other articles made of textile fabrics, the general technique involves exposing the garments, etc., to the action of a bath consisting of a solvent such as mineral spirits, trichloroethylene, perchloroethylene or trifluorotrichloroethane, containing from about 0.5 to 5.0% of a detergent, and a very small amount—from about 0.02 to 0.12%—of water, using from about 5 to 20 times as much bath as weight of fabric. The bath is circulated through the garments for a short period of time, typically 5 to 20 minutes at room temperature, picking up in the process particles of dirt which become suspended in the bath, dissolving such materials as greases and oils, which are soluble in the solvent, and emulsifying any water which may be present in the garments. After separation from the garments, the liquid may be reused as it, or treated with a dehydrating agent to reduce its water content, or filtered to remove the solid matter removed from the garments. Eventually, the solvent must be distilled to clean it up. The distillation is the most expensive way to clean up the solvent, since it entails both operational costs and loss of the expensive detergent, which must be replaced. Hence, it is desirable to reduce the frequency of distillation.

STATEMENT OF THE INVENTION

We have found that, surprisingly, treatment of dirty dry cleaning baths with aqueous hydrogen peroxide by simple agitation at room temperature for short periods of time, with at least enough aqueous hydrogen peroxide to just more than saturate the bath, followed by distillation, results in sufficient cleaning of the dirty baths so that distillation can be postponed for a sufficient time to permit substantial cost savings.

DETAILED DESCRIPTION OF THE INVENTION

The typical dry cleaning baths, consisting essentially of solvent and solvent-soluble detergents, will hold small amounts of water in the system, of the order of a few tenths of a percent. This water helps the detergent in the cleaning process, to dislodge water-soluble dirt, while the oil-soluble dirt is dissolved by the solvent. This pick-up of dirt in the process, which cleans the clothes, dirties the solvent.

Typically, a clean dry cleaning bath—for example, perchloroethylene containing 1% of a typical detergent such as the isopropylamine salt of dodecylbenzene sulfonate—will have a high transmission of light, ranging from 91%

2

for light at 450 m μ to 94.2% at 500 m μ , to 99.1% at 600 m μ . When the transmission at 500 m μ drops to the vicinity of 50% (after the filtration which it generally undergoes after each cleaning cycle), the cleaning bath is generally considered too dirty for further cleaning and is distilled. This costs about twenty-five cents per 100 pounds of solvent, plus the cost of the detergent which must be added to reconstitute the cleaning bath.

We have found that if dirty dry cleaning baths heretofore considered unfit for use without distillation are treated with aqueous hydrogen peroxide, sufficient clean-up can be obtained to permit the reuse of the bath without distillation, if the bath is treated with more hydrogen peroxide than the bath will hold in the system—i.e., more than a few tenths of a percent of combined peroxide and water. If insufficient hydrogen peroxide is present to more than saturate the bath, substantially lower cleaning efficiency is obtained than when the same amount of hydrogen peroxide is used together with enough water to more than saturate the system.

We believe there is a dual action taking place. There is bleaching action by the peroxide which decreases the light absorption. But a major proportion of the clean-up appears to be due to some physical effect on the suspended dirt by the fine particles of excess aqueous peroxide suspended in the system, which we believe act as nuclei for the agglomeration of small dirt particles to a size where they will filter out. This view is reinforced by experimental evidence. For example, a dirty perchloroethylene bath whose transmittance had fallen to 53% of 500 m μ was treated with 0.5% of 50% aqueous hydrogen peroxide for 30 minutes at 25° C. The mixture was filtered through diatomaceous earth in conventional fashion, and had a transmittance of 66%. The same solvent, treated with the same amount of water under the same conditions, had a transmittance of 60%. The same solvent, treated to remove water, and then treated with 0.255% of 98% hydrogen peroxide, also had a transmittance of about 60%, indicating that the action is only about half-bleaching.

The amount of aqueous hydrogen peroxide needed depends on the bath, since the water-carrying capacity varies with both solvent and detergent. However, the actual amount of peroxide used need not vary, since more or less water can be added with it. Since water alone in sufficient quantity produces an improvement, any amount of peroxide will contribute its bleaching power. Up to about 0.25% of hydrogen peroxide (100% basis), based on bath weight, there is a definite increase in transmission as peroxide increases; above about this figure, the additional transmission per unit falls off, and becomes uneconomic, at points which vary with the composition of the bath, and the nature of the dirt picked up in the cleaning process, and the concentration of the peroxide. Amounts of peroxide above about 0.5% are, in general, economically unattractive.

SPECIFIC EXAMPLES OF THE INVENTION**Example 1.—Perchloroethylene bath**

A dry cleaning bath containing perchloroethylene with 1% of the isopropylamine salt of dodecylbenzene sulfonate was prepared; its light transmittance was 450 m μ —91%; 500 m μ —94.2%; 600 m μ —99.1%. It was used in cleaning until its transmission at 500 m μ dropped to 50%, and was treated with 0.25% of hydrogen peroxide, in one case as 98% H₂O₂, in the others as 50% H₂O₂, by

stirring the peroxide into the dirty bath and filtering through diatomaceous earth; the following transmissions were measured on the sample:

	Transmission at—		
	450	500	600
0.255 weight percent H ₂ O ₂ (98%)-----	43	59.7	72.3
0.5 weight percent H ₂ O ₂ (50%)-----	46	66.0	81.0

The physical effect of more water plus peroxide than the system will hold is clearly demonstrated.

Example 2.—Stoddard solvent

A stoddard solvent dry cleaning bath obtained from a local dry cleaner, which he considered too dirty for further work and which had a transmission at 500 m μ of 52.5%, was treated as in Example 1 with 0.5% by weight of 50% hydrogen peroxide; the transmittance rose to 68% at 500 m μ .

Obviously, the examples can be multiplied indefinitely without departing from the scope of the invention as defined in the claims.

We claim:

1. The method of treating dirty dry cleaning baths consisting of a volatile oil solvent and a detergent to permit longer operation between distillations, which comprises agitating the dirty bath with at least 0.25% aqueous hydrogen peroxide, and filtering the bath to remove suspended dirt and fine particles of excess aqueous hydrogen peroxide to obtain a cleaned bath.

2. The method of claim 1, in which the hydrogen peroxide is not in excess of 0.50% of bath weight.
